UNITED STATES PATENT OFFICE.

THOMAS TATLOW TANNEHILL, OF TORONTO, ONTARIO, CANADA.

DESIGN FOR A COMBINED FLOOR LAMP AND SOUND AMPLIFIER.

Application filed December 17, 1926. Serial No. 20,069. Term of patent 3½ years.

To all whom it may concern:

Be it known that I, THOMAS TATLOW TANNEHILL, a citizen of the United States, residing at the city of Toronto, in the county of York and Province of Ontario, Dominion of Canada, have invented a new, original, and ornamental Design for a Combined Floor Lamp and Sound Amplifier, of which the following is a specification, reference

being had to the accompanying drawing, forming part thereof.

The figure is a perspective view of a combined floor lamp and sound amplifier, showing my new design.

I claim:

The ornamental design for a combined floor lamp and sound amplifier, as shown.

THOMAS TATLOW TANNEHILL.
